UNITED STATES PATENT OFFICE.

JOHN HENRY BALMER, OF MAPLEWOOD, NEW JERSEY, ASSIGNOR TO J. H. BALMER CO., OF NEWARK, NEW JERSEY, A CORPORATION OF NEW JERSEY.

DESIGN FOR A TOWEL-BAR POST.

Application filed April 8, 1925. Serial No. 13,069. Term of patent 14 years.

To all whom it may concern:

Be it known that I, JOHN HENRY BALMER, a citizen of the United States, and resident of Maplewood, in the county of Essex and State of New Jersey, have invented a new, original, and ornamental Design for a Towel-Bar Post, of which the following is a specification.

Reference is had to the accompanying drawing in which—

Fig. 2 is a similar perspective as viewed from the inner side.

I claim:

The ornamental design for a towel bar post as shown.

JOHN HENRY BALMER.
